UNITED STATES PATENT OFFICE.

EDWARD BEALS CARPENTER, OF PLYMOUTH, INDIANA.

CARD.

SPECIFICATION forming part of Letters Patent No. 740,228, dated September 29, 1903.

Application filed February 27, 1903. Serial No. 145,320. (No model.)

To all whom it may concern:

Be it known that I, EDWARD BEALS CARPENTER, a citizen of the United States, and a resident of Plymouth, in the county of Marion and State of Indiana, have invented a new and Improved Card, of which the following is a full, clear, and exact description.

My invention relates to certain novel and useful improvements in cards, and has particular application to visiting-cards, display-cards, or the like.

One of the important objects of my invention is to provide a card which may be readily attached to any projection, such as a door-knob or the like, the shape of the article being such that the likelihood of the card being disturbed or lost will be obviated.

A further object of the invention is to provide my improved card with a tongue or extension cut from the material of the blank, such tongue serving as a support or brace for the card when it is desired to apply the same in an upright position.

As is well known it is often desirable to leave a memorandum-card at the place of business or at the residence of an absent party, and it is the general practice to either place such cards on the shank of a door-knob or slide the same beneath the door, the result being that the card is either knocked from the door and lost or else is passed unnoticed; but an invention such as I have devised will enable a card to be supported in an upright position where it will attract attention.

To the accomplishment of the above-recited ends and those of a similar nature, the invention consists in the construction, combination, and arrangement of parts as are described in this specification, illustrated in the accompanying drawings, and set forth in the annexed claim.

Reference is to be had to the accompanying drawings, forming a part of this specification, in which similar characters of reference indicate corresponding parts in all the figures.

Figure 1 is a view of a portion of a door, showing the manner of applying my improved card thereto. Fig. 2 is a vertical sectional view taken through a portion of a door having my card applied thereto and showing the tongue of the card acting as a brace or sup-

port. Fig. 3 is a face view of one of my improved cards. Fig. 4 is a perspective view of the same, showing the tongue bent backward and acting as a support; and Fig. 5 is a vertical sectional view taken on the line 5-5 of Fig. 4.

Referring now to the accompanying drawings, the letter A designates a portion of a door to the shank B of the knob C whereof is applied my improved card. As will be seen, particularly upon reference to Figs. 3, 4, and 5, this card comprises an ordinary plain blank 1, which may be of cardboard or the like, and approximately centrally of one edge of the card, as at 2, I make a cut or incision 3, preferably semicircular or circular in shape, but do not sever the tongue portion 4 thus formed entirely from the body of the card. The tongue 4 is formed integral with the card-blank, and when it is desired to use the same as a support to enable such card or blank to be retained in an upright position the tongue may be bent backward approximately along the line x-x (shown in Figs. 3 and 4) until said tongue assumes the position plainly illustrated in Figs. 4 and 5. If it is desired to place the card upon the shank of a door-knob or in a like position, instead of bending the tongue back the latter may be bent forward, as shown in Figs. 1 and 2, thereby enabling the card to be held with the printed matter, such as the name or address, plainly in view.

There are many advantages incident to my improvement which will immediately suggest themselves. For instance, when the card has an advertisement or price-mark printed thereon the tongue and incision may be so formed that the card may be easily and securely attached to articles, such as shoes or hats, displayed in a store-window. When the card is employed for social or visiting purposes, the tongue is so formed that the card will be supported in an upright position on a table or desk or the like. The numerous other advantages incident to my invention are so apparent that it is unnecessary to dwell upon the same here in detail.

Having thus described my invention, I claim as new and desire to secure by Letters Patent—

A card having a relatively small curved incision at the lower edge portion thereof, the point of meeting of the side walls of the incision and the lower edge of the card forming sharp, oppositely-turned points in the card designed when the latter is attached to a cylindrical object, to partially encircle and securely engage the same, and a tongue formed integral with the card by said in-

cision, said tongue forming a support for 10 said card, substantially as set forth.

In testimony whereof I have signed my name to this specification in the presence of two subscribing witnesses.

EDWARD BEALS CARPENTER.
